UNITED STATES PATENT OFFICE

2,518,952

STRIPING MACHINE

Carl G. Schner, Tacoma, Wash.

Application June 4, 1947, Serial No. 752,459

2 Claims. (Cl. 91—12)

1

This invention comprises novel and useful improvements in a striping machine and more specifically pertains to an attachment which may be applied to trucks for striping or marking traffic lanes of highways from the moving truck.

The principal object of this invention consists in providing an apparatus which shall be capable of simultaneously striping or painting traffic lane markers for a plurality of traffic lanes from a moving truck.

An additional purpose of the invention is to provide an apparatus in conformity with the foregoing object, wherein the device may be easily applied to or removed from a highway truck.

A still further object of the invention is to provide an attachment in conformity with the foregoing objects, having improved paint spraying mechanism for producing a clear painted line of any desired width.

Yet another important object of the invention consists in providing a road marking apparatus according to the preceding objects which may be readily collapsed against the body of a truck for easy transportation and convenient storage when not in use.

These, together with various and ancillary objects of the invention which will later become apparent as the following description proceeds, are attained by this device, a preferred embodiment of which has been illustrated, by way of example only in the accompanying drawings, wherein:

Figure 1 is a perspective view showing the attachment applied to a truck for transportation by and use therewith;

Figure 2 is a diagrammatic rear elevational view showing the device applied in operative position to the rear of the truck shown in Figure 1;

Figure 3 is a diagrammatic top plan view of the construction shown in Figures 1 and 2;

Figure 4 is a perspective view of a portion of the attachment, showing one of the paint striping units;

Figure 5 is a fragmentary side elevational view of a part of a truck showing the device applied thereto; and

Figure 6 is a perspective view of a detail, showing a part of the adjusting means of the mechanism.

Referring now more specifically to the annexed drawings, wherein like numerals designate similar parts throughout the several views, there is indicated generally as shown in Figure 1, a truck 10 of any suitable construction and which

2

in this instance is depicted as a conventional type of truck employed by the highway departments of various states.

Conveniently and suitably mounted in the body of the truck 10, is an air compressor 12 and a paint storing and agitating tank 14 of suitable design. At the rear of the truck is preferably provided a cantilever type of platform 16 to accommodate and support the operator of the striping device.

Suitable conduits, gauges and control valves are provided for delivering the air and paint to the mixing nozzles of the spraying devices, such conduits forming in themselves no part of this invention.

As shown best in Figures 2, 3 and 6, a transverse support bar of any suitable construction and indicated at 18 is mounted rearwardly of the rear wheels of the truck and supported as by brackets 20 from the platform 16 or any suitable part of the framework of the truck. Detachably connected to the extremities of the support member 18, are a pair of laterally extending outriggers 22 which are pivotally connected thereto as at 24, and are detachably braced from the framework of the truck as by reinforcing means 26 detachably fastened as at 28.

The outriggers 22 are preferably of tubular construction and telescopingly receive extension members 30 which are slidable therein and are adjustable longitudinally thereof as by wing nut fastening means 32.

Adjacent the outer extremities of the extension rods 30, are provided forwardly extending, rigidly attached U-shaped frames 34 within which are journaled pneumatically tired wheels 36 for supporting the outer extremities of the outriggers. This construction is shown more clearly in Figure 4.

A plurality of paint spraying nozzles are adjustably mounted upon the support bar 18 and the outrigger extension 30 in longitudinally spaced position, each of these painting units being preferably constructed as indicated in Figure 4. Each unit comprises spraying nozzles 38 of any suitable type and construction and which are adapted to discharge an atomized spray of paint and air under pressure, the construction of this nozzle forming in itself no part of this invention. These spray nozzles are preferably mounted in any suitable manner upon the support rod 18 and the extension rods 30, and are connected by suitable flexible conduits to the source of compressed air and the paint tank. 55 Disposed slightly below each nozzle and upon

opposite sides thereof, are a pair of adjustable shields or paint guards for regulating the width of the stripe which is to be painted upon the surface of a road or the like. For this purpose, a plurality of clamps 40 are slidably received upon the support bar 18 and rod extensions 30 and are secured in longitudinally adjusted position thereon as by set screws 42. Horizontally disposed and forwardly or rearwardly extending support rods 44 are adjustably attached to the clamps 40 as by means of further fastening means 46. The outer extremities of the rods 44 are provided with shields or guards 48 of generally rectangular shape, and which are preferably disposed at an acute angle, such as 45°, with the surface to be painted, in such position relative to the nozzle 38, as to limit the spreading of the spray therefrom, and thereby confine the spraying paint to a predetermined width upon the surface to be painted. Obviously, the support rods 44 may be rotated or otherwise adjusted in the clamps 40 to vary the distance between their lower extremities, and thereby regulate the width of strip painted upon the highway.

It will thus be seen that when both of the outriggers are positioned in their operative assembled relation, as shown in Figures 2 and 3, a plurality of stripes for traffic lanes may be painted upon a surface such as a road, airport, or any other environment, at a predetermined width between the stripes and with a predetermined width of stripe, and applied either as a continuous line or as a broken line as desired.

In order to vary the relative position of the spray units with respect to the truck upon which the same are mounted, during operation of the truck, a lateral adjusting means, shown more clearly in Figures 5 and 6, is provided. A control wheel 50 positioned within easy access of the operator stationed upon the platform 16, is mounted upon a shaft 52 suitably journaled in the framework of the truck, suitably attached to the shaft 52 is an operating mechanism which may consist of a conventional cam and lever construction, indicated generally at 54, and provided with an arm 56 which is oscillatable by the mechanism 54 and is pivotally connected as at 58 to a drag link 60 whose extremity is pivotally attached as at 62 to a clamp 64 engaging the support bar 18. It will thus be seen that as the wheel 50 is rotated, the operating mechanism above described will shift the support rod 18 laterally with respect to the truck 10, in order to enable the operator to paint stripes of a curved shape or of varying displacement relative to the truck, as desired.

As will be understood, one or both of the outriggers 22 may be folded up against the side of the truck, as indicated in dotted lines in Figure 2, when the operation of that portion of the device is not desired. This readily facilitates the passage of the truck through cramped spaces, facilitates the movement of the truck in traffic when the devices for painting are not to be employed, and in general renders the attachment more portable in its nature.

From the foregoing, it will be seen that there has been provided a striping attachment for

highways or the like, wherein one or a plurality of traffic stripes may be simultaneously painted while the truck is operated at a relatively high speed, and wherein the bosses may be appropriately positioned upon the roadbed without having a fixed relation to the position of the truck.

Since numerous modifications will readily occur to those skilled in the art after a consideration of the foregoing specification and accompanying drawings, it is not desired to limit the invention to the exact construction shown and described, but all suitable modifications and equivalents may be resorted to falling within the scope of the appended claims.

Having described the invention what is claimed as new is:

1. In a striping machine of the type described the improvement comprising: a support bar mounted on a truck and adapted to support a striping device, a clamp on said support bar, a drag link pivotally connected to said clamp, an oscillatable arm pivotally connected to said link and adapted to reciprocate said bar with respect to the truck, said striping device including spray means for dispensing a striping material, a pair of guards adjustably mounted on said bar and having edges defining the width of the stripe and positioned on each side of said spray means, and said bar having means for adjustably securing said guard edges in preselected angular relation to each other and to the surface being striped.
2. A striping machine comprising a support bar, means for mounting said support bar on a truck, a plurality of paint striping units on said bar, each of said units comprising a paint and air mixing nozzle, a pair of guards on opposite sides of each nozzle for regulating the width of the paint spray discharged from each nozzle and means for adjusting the spacing of said guards with respect to each other, comprising pairs of clamps slideable and rotatable upon said bar, an arm on each guard, each arm being rotatably mounted on one of the clamps for rotation about an axis perpendicular to that of the bar, wherein said bar is mounted for longitudinally slideable movement, and means for moving said bar comprising a central shaft, and a connecting link pivotally connected to said bar and shaft.

CARL G. SOHMER.
